UNITED STATES PATENT OFFICE

HENRY M. REED, JR., OF LOUISVILLE, KENTUCKY, ASSIGNOR TO STANDARD SANITARY
MANUFACTURING COMPANY, A CORPORATION OF NEW JERSEY

WALL JOINT FOR PLUMBING FIXTURES

Application filed August 1, 1931. Serial No. 554,589.

This invention relates to the installation of plumbing fixtures, and more particularly to new and improved means for forming a water-tight joint between the fixture and the wall sheathing. In the installation of bath or similar fixtures in which the fixture is placed into a corner of a room or into an alcove especially designed for the purpose difficulty has been experienced in providing a water-tight connection between the fixture and the sheathing covering the wall of the room and especially where the sheathing was made of enameled sheet metal panels.

It is an object of this invention to provide a joint between a plumbing fixture and an enameled sheet metal sheathing which will be water-tight and free from sharp edges so as to prevent injury to persons accidentally coming in contact therewith.

Another object of this invention is to provide means for forming a water-tight joint between a plumbing fixture and a sheet metal wall panel which is readily removable so as to permit access to the area behind the paneling.

A still further object of this invention is to provide means for forming a water-tight joint between a plumbing fixture and a sheet metal wall panel which will be relatively simple to manufacture, easy to install and positive in operation.

These and other objects which will be hereinafter made apparent to those skilled in this particular art are accomplished by means of this invention, one embodiment of which is described in the following specification and illustrated in the accompanying drawing, wherein;

Figure 1 is a view in perspective of a bath alcove equipped with enameled sheet metal sections joined to a plumbing fixture in accordance with my invention; and

Fig. 2 is an enlarged fragmentary view in section showing in detail the joinder be-

tween the fixture and the sheet metal sheathing.

Referring to the drawing in detail, 1 designates a bathtub which is designed to be positioned in a corner or alcove provided for that purpose in a bathroom or the like, having walls 2. The tub 1 is provided with a rim or splash strip 3 on the sides thereof which abut against the walls 2 of the room. So that the walls of the room will be protected from splashing water and made more attractive and sanitary, sheet metal panels 4 are provided which form a covering or sheathing for the wall. The panels 4 are spaced from the walls 2 of the room and the upper edges are fastened to nailing or furring strips (not shown). The rim or splash strip 3 on the tub extends underneath the lower ends of the panels.

In order to secure a watertight joint between the panels 4 and the tub, I bend or crimp inwardly the lower ends of the panels adjacent the splash strip 3, so as to form brackets 5 of substantially N-shape thereon which engage members, or plates 6 secured to the splash strip 3 of the tub. The members 6 which may be formed of any suitable material and attached to the splash strip in any suitable way, project upwardly above the splash strip and form a base on which the panels 4 rest.

As is clearly shown in the drawing, I prefer to have the members 6 of such height that the lowermost edges of the panels 4 are slightly above the splash strip 3. This construction protects the tub and prevents injury to the enamel thereon when the panels are being installed on the tub.

Waterproof cement may be applied in the space between the members 6 and the portion 5 of the panels, if desired.

While I have illustrated my invention as applied to a bathtub, it is understood that it is not limited thereto, but may be applied to any plumbing fixture or the like where

it is desirable to form a joint between the fixture and a metallic wall sheathing.

It is readily apparent that a joint constructed in accordance with my invention is 5 water-tight and free from sharp edges since the sheet metal sections forming the sheathing are bent back upon themselves and no cut edges are exposed. It is also apparent that a metallic wall panel joined to a fixture 10 in accordance with my invention may be readily assembled and dismounted.

What I claim as new and desire to secure by Letters Patent is:

1. In combination, a wall, a sheathing for 15 said wall formed of sheet metal panels having a crimped lower edge, a plumbing fixture having a splash strip abutting said wall and extending beneath the lower end of said sheet metal panels, and means secured to 20 said splash strip and engaging the crimped lower ends of said sheets for forming a joint therebetween.

2. In combination, a wall, a covering for 25 said wall formed of a plurality of sheet metal sections having the lower ends thereof bent so as to form a bracket thereon, a plumbing fixture having a portion thereof extending underneath said sheet metal sections, and means secured to 30 said fixture and cooperating with the brackets on said sheet metal sections for supporting the same and for forming a water-tight joint between said sections and said fixture.

3. In combination, a wall, a finishing 35 sheathing for said wall having the lower edge bent inwardly into a series of return bends, a plumbing fixture adjacent said wall having a portion thereof projecting underneath the bent portion of said sheathing, and a member secured to 40 said fixture and projecting upwardly therefrom for receiving the bent lower edge and for supporting the sheathing in spaced relation to said fixture.

4. In combination, a wall, sheet metal panels secured to 45 said wall forming a sheathing therefor, and having the lower ends thereof bent so as to form a bracket of substantially N-shape, a plumbing fixture, a rim on said fixture abutting said wall, a member secured to 50 said rim and projecting upwardly therefrom for engaging said bracket, and means disposed between said member and said bracket for forming a water-tight joint therebetween.

5. The combination with a room having 55 a plumbing fixture disposed in a corner thereof, of a sheet metal covering spaced from the walls of said room and having the edges thereof adjacent said fixture bent inwardly into a series of return bends and extending over the rim of said fixture, and means secured to the rim of said fixture for receiving the bent edge of said covering and supporting it on said fixture.

6. The combination with a room having a 60 plumbing fixture disposed in a corner thereof, of a sheet metal wall covering spaced from the walls of said room and having the edges thereof adjacent said fixture bent inwardly in 70 a series of reverse bends forming a bracket thereon, a rim on said fixture extending under the bracket formed on said covering and members secured to said rim for receiving said bracket and supporting the 75 covering in spaced relation to said fixture.

In testimony whereof, I have hereunto subscribed my name this 30th day of July, 1931.
